Attorney, Agent, or Firm—Raymond C. Stewart

[57] CLAIM

The original design for a poultry nest bank unit, as shown and described.

DESCRIPTION

FIG. 1 is a perspective view taken from the front and right side of a poultry nest bank unit showing my new design;

FIG. 2 is a perspective view taken from the rear and right side thereof, showing the top egg tray cover in its raised position;

FIG. 3 is a top plan view of FIG. 1; and

FIG. 4 is a right side elevational view of FIG. 1, the left side being a mirror image of the right side shown.

FIG. 1

FIG. 4

FIG. 2

FIG. 3
